UNITED STATES PATENT OFFICE.

VICTOR E. EDWARDS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

APPARATUS FOR COILING, COATING, AND COOLING WIRE RODS.

1,075,702.

Specification of Letters Patent.

Patented Oct. 14, 1913.

Original application filed October 5, 1908, Serial No. 456,143. Divided and this application filed December 1, 1909. Serial No. 530,845.

To all whom it may concern:

Be it known that I, Victor E. Edwards, a citizen of the United States, residing at Worcester, in the county of Worcester and 5 Commonwealth of Massachusetts, have invented a new and useful Improvement in Apparatus for Coiling, Coating, and Cooling Wire Rods, of which the following is a specification, forming a division of my application for a process and apparatus for 10 coiling, coating, and cooling wire rods filed on or about October 5, 1908, Serial No. 456,143, accompanied by drawings forming a part of the same, in which—

15 Figure 1 is a plan view of an apparatus embodying my invention. Fig. 2 is a sectional view, and Fig. 3 is a detached plan view of the coil supporting plate.

20 Similar reference characters refer to similar parts in the different views.

The object of my invention is to provide 25 an improved apparatus for coiling, coating and cooling metal rods from a rolling mill by a single operation, by which the rods are partially cooled during the operation 30 of coiling, oxidation of the rods is reduced during the coiling process, the freed scale is removed from the apparatus, a coating material is applied to the rod and the manipulation of the coils is facilitated. I accomplish these results by coiling the rods in a closed receptacle in which the rod as it 35 is coiled is submerged in water, preferably containing a suitable coating material, during the entire process of coiling, and providing means whereby the water and freed scale may be removed from the coiling receptacle at each operation, and also by providing means to facilitate the removal of the 40 coil.

By my improved apparatus, as herein described and pointed out in the annexed claims, the rods as they are delivered from the rolling mill are coiled, coated preparatory to drawing and sufficiently cooled while being coiled, requiring but a single operation between the rolling mill and the drawing die and requiring for the entire operation only the time consumed in coiling.

45 The mechanism employed in laying the heated rod into a coil, as it is received from the rolling mill, may be of any known type now in use, so long as means are provided

for the retention of a body of water sufficient to immerse the entire coil during the 55 process of coiling.

Referring to Fig. 2 of the accompanying drawings, 1 denotes a water receptacle cylindrical in cross section, and having an inclined bottom 2, mounted upon a shaft 3, 60 capable of being reciprocated vertically in order to raise and lower the water receptacle. In the present instance the rod forms the plunger of a hydraulic elevator. Supported upon a vertical framework 4 is a 65 dome 5 provided on its rear with an interior flange 6 extending approximately half way around the dome. To the flange 6 is attached a semicircular depending plate 7 extending downwardly into the receptacle 1, 70 and to the lower edge of the plate 7 is attached an inclined stationary coil supporting plate 8 parallel with the bottom 2. The plate 8 is provided with openings to receive the coil centering pins 9, which are attached 75 to and extend upwardly from the bottom 2 concentric with the axis of a rotating rod laying tube 10. The rod laying tube 10 is carried by a rotating shaft 11 journaled in a bearing 12, supported upon the top of the 80 dome 5. The rod delivered from the last pair of rolls in the rolling mill is conducted by a tube 13 and delivered to the rotating rod laying tube 10. The mouth 14 of the rod laying tube 10 is arranged to deliver the 85 heated rod in a coil within the annular space surrounding the centering pins 9 and in front of the semicircular depending plate 7. The receptacle 1 is provided on its front side with a lip 15 overlapping the conveyor 90 table 19. The receptacle 1 is connected with a source of water supply by means of a flexible pipe 16, and the overflow lip 15 maintains a water level sufficient to submerge the coil of wire 17 and also to reach the mouth 95 14 of the laying tube 10, so that the heated rod is delivered in the body of water as soon as it leaves the laying pipe 10. When the coil 17 has been completed, the receptacle 1 is lowered into the position indicated 100 by the broken lines 18, carrying the top of the receptacle below the plane of the inclined coil supporting plate 8 and withdrawing the centering pins 9 from the coil.

The inclination of the coil supporting plate 105 8 is preferably not sufficient to cause the

coil 17 to be delivered from the plate by gravity, but its inclination facilitates the removal of the coil downward upon a receiving table 19 and against an upturned flange 20 on the outer side of the table, which places the coil in the position shown by the broken lines 21, where they are engaged by the vertical pins 22 carried by a moving chain 23, which causes the removal of the coils from the table 19. The receptacle 1 is raised from its lowered position into the position shown by solid lines in Fig. 2, and the operation of coiling repeated. The lowest corner of the receptacle 1 is provided with an opening 24 which is closed by a valve 25, having a depending valve stem 26 extending below the receptacle and arranged to be lifted by its contact with the framework when the receptacle is depressed, as shown at 27, allowing the water contained in the receptacle 1 and any scale which may have accumulated to flow out of the receptacle into a conduit 28. Air is excluded from the heated rod after its delivery from the mouth 14 of the laying tube until the coil is completed, and the partial cooling of the rod is accomplished uniformly throughout its entire length, usually during the time required for coiling, but the period of cooling may be extended, if desired. The amount of cooling can also be varied during the period of coiling by varying the flow of water supply through the pipe 16, so as to give a higher or lower temperature to the water in the receptacle 1. The water supply pipe is provided with a branch pipe leading to a reservoir 29 of water, containing a suitable coating material such as is now employed in coating rods preparatory to drawing, which is carried by the water in the reservoir into the receptacle 1 and adheres to the surface of the coiled rod to prepare it for its passage through drawing dies. The supply pipe is provided with a stop cock 30 which enables the flow of water to the receptacle 1 to be increased to lower the temperature of the water in the receptacle 1, or decreased to permit the temperature to be raised by the heat of the rod and thereby varying the amount of cooling during the operation of coiling. The pipe leading to the clear water supply is provided with a stop cock 31, and the branch pipe to the reservoir 29 has a stop cock 32, enabling the amount of coating material carried into the receptacle to be regulated.

I claim,

1. The combination in an apparatus for coiling rods, of a framework, a plate depending from said framework, a coil supporting plate held by said depending plate, a water receptacle normally inclosing said coil supporting plate, and means for lowering said receptacle below the plane of said coil supporting plate.

2. The combination in an apparatus for coiling rods, of a stationary framework, a coil supporting plate held by said framework, a water receptacle inclosing said plate, means supported by said receptacle for centering the coil formed on said plate, and means for vertically reciprocating said receptacle to allow for the sidewise removal of the coil from said plate.

3. The combination in an apparatus for coiling rods, of a coil-supporting plate, a movable water receptacle inclosing said plate, means for supplying a current of water to said receptacle, and means for automatically discharging the water from the receptacle when the latter is removed from the coil-supporting plate.

4. The combination in an apparatus for coiling rods, of a coil supporting plate, a water receptacle inclosing said plate, means for supplying water to said receptacle, means for lowering said water receptacle below the plane of said plate, and means for automatically removing water from said receptacle by its downward movement.

5. The combination in an apparatus for coiling rods, of a stationary coil supporting plate, a water receptacle inclosing said plate, means for supplying a current of water to said receptacle, means for lowering said receptacle below the coil supporting plate, and a rotating laying tube having its delivery end inclosed in said water receptacle when the latter is in its raised position.

6. The combination in an apparatus for coiling rods, of a stationary coil-support, a water receptacle normally inclosing said support, a stationary dome located above and in the path of the receptacle, and means for lowering said receptacle from said dome and below the plane of said coil support.

7. The combination in an apparatus for coiling rods, of a water receptacle, a stationary cover for said receptacle, a coil supporting plate supported by said cover, means supported by said receptacle for centering said coil on said plate, and means for vertically reciprocating said receptacle to allow for the sidewise removal of the coil from said plate.

8. The combination in an apparatus for coiling rods, of a water receptacle cylindrical in cross section, having an inclined bottom and mounted on a shaft capable of being reciprocated vertically, a stationary cover above said receptacle with a semicircular depending plate extending downward into the receptacle, and a coil supporting plate attached to the lower end of said depending plate parallel with the bottom of said receptacle, coil centering means for a coil on said plate, said means attached to said receptacle, and means for coiling a rod on said supporting plate around said centering means.

9. In an apparatus for coiling metal rods, the combination with a receptacle for the coiled rods, of a water supply pipe for said receptacle, a tank for a coating material, a pipe connecting said tank with said water supply pipe, means for regulating the flow of water through said supply pipe, and means for regulating the supply of coating material to said water supply pipe.
10. In an apparatus for coiling rods, a stationary supporting plate for the coil, a water receptacle inclosing said plate, means for maintaining a flow of water through said receptacle from the bottom toward the top, means for lowering said receptacle from its normal position, and means for withdrawing the water from the receptacle when in its lowered position.
11. In an apparatus for coiling, coating and cooling wire rods, the combination of a water receptacle having an inclined bottom, and means for raising and lowering the latter, of a dome in position to be engaged by the upper edge of the water receptacle when the latter is in one of its extreme positions, the dome provided with a depending flange extending part-way around the latter, and a semi-circular depending plate extending downwardly from the dome into the water receptacle, and an inclined stationary coil-supporting plate attached to the semi-circular depending plate.
12. In an apparatus for coiling, coating and cooling wire rods, the combination of a water receptacle having an inclined bottom, and means for raising and lowering the latter, of a dome in position to be engaged by the upper edge of the water receptacle when the latter is in one of its extreme positions, and a semicircular depending plate extending downwardly from the dome into the
- water receptacle, and an inclined stationary coil-supporting plate disposed approximately parallel with the inclined bottom of the receptacle, and attached to the semi-circular depending plate. 45
13. In an apparatus for coiling, coating and cooling wire rods, the combination with a conveyer table, a dome, an inclined coil-supporting plate depending from and supported by the dome, of a water receptacle adjacent to the conveyer table and located beneath the dome, said water receptacle provided with a lip overlapping the conveyer table, and means for raising and lowering the receptacle with respect to the inclined coil-supporting plate and the conveyer table. 50
14. In an apparatus for coiling, coating and cooling wire rods, the combination with a conveyer table, a dome, an inclined coil-supporting plate depending from and supported by the dome, of a water receptacle adjacent to the conveyer table and located beneath the dome, said water receptacle provided with a lip overlapping the conveyer table, means for raising and lowering the receptacle with respect to the inclined coil-supporting plate and the conveyer table, 55 means for supplying a current of water at a point at or near the bottom of the water receptacle, and means located at the lowermost point of said bottom, which automatically discharges water from the receptacle when the latter is lowered away from the coil-supporting plate. 60
